(57) CLAIM

I claim the ornamental design for a planter, as shown and described.

DESCRIPTION

FIG. 1 is a perspective view of a planter, showing my new design;

FIG. 2 is a top plan view thereof;

FIG. 3 is a bottom plan view of the thereof;

FIG. 4 is a left side elevation view thereof, the right side elevation view being identical thereto; and,

FIG. 5 is a front elevation view thereof, the rear elevation view being identical thereto.

The broken line areas on the Figures are showing environmental subject matter only and form no part of the claimed design.
